ROLLING MILL WITH SEGMENTAL ROLLS

Frederick Andrew McNulty, Bedford, England, assignor to W. H. A. Robertson & Company Limited, Bedford, England

Application July 23, 1956, Serial No. 599,619

Claims priority, application Great Britain August 5, 1955

1 Claim. (Cl. 80—14)

This invention relates to rolling mills of the kind comprising a reciprocating roll-carrying housing, and means including a rack-and-pinion mechanism for imparting rotational motions from the housing to the rolls. Mills of this kind are used for such purposes as reducing or otherwise shaping metal tubes or bars.

When it becomes necessary to recondition the rolls, a machine of the kind aforesaid and of previously known construction must of necessity be put out of action for the time required to effect the reconditioning with consequent loss of productivity.

The object of the present invention is to enable the above disadvantage to be obviated in a simple and convenient manner.

A mill of the kind aforesaid and in accordance with the invention comprises the combination of a reciprocating carriage, and a self-contained roll unit removably mounted on the carriage, the said unit being replaceable by a stand-by unit.

In the accompanying drawings:

Figure 1 is a front elevation and Figure 2 a cross section on the line 2—2 of Figure 1 illustrating a self-contained roll unit in accordance with the invention.

Figure 3 is a side elevation, Figure 4 a plan, and Figure 5 a cross section on the line 5—5 of Figure 3 illustrating a mill provided with the unit shown in Figures 1 and 2.

Referring to the drawings, there is provided a bed 6 on which are formed a pair of parallel horizontal tracks 7. Also on the bed, and at the same level as the tracks, are mounted a pair of horizontal racks 8. On the bed is supported a carriage 9 which consists essentially of a rectangular frame, the carriage being supported on the said tracks 7 by rollers 10. Reciprocating motion is imparted to the carriage 9 by an oscillatory arm 11 which

2

at one end is connected by links 12 to the carriage and which at the other end is connected to links 13, the latter being actuated by a crank mechanism (not shown).

The roll unit consists of a housing 14 on which are mounted a pair of interacting rolls 15 having working grooves formed on the rolls, or on inserts removably secured to the rolls. Preferably the housing comprises upper and lower parts each adapted to carry a roll, the two parts being held together by hydraulically pre-stressed bolts 16 in a known manner.

The rolls are interconnected by pairs of pinions 17 on the ends of the roll spindles, and on each end of the upper roll spindle is also secured a pinion 18 for engagement with the corresponding rack 8 on the bed.

15 The roll unit is detachably mounted on the carriage and is secured thereto by keys, wedges or other means.

When it is required to recondition the rolls, it is merely necessary to release the roll unit and after lifting it off the carriage replace it by a stand-by unit, the whole operation being capable of being performed in a short time and without disturbance of any other part of the mills.

Having thus described my invention what I claim as new and desire to secure by Letters Patent is:

25 A rolling mill comprising in combination a supporting base, a carriage having a pocket open at its upper end, said carriage being movably supported on the base, mechanism connected to the carriage for imparting linear reciprocatory movements to the carriage, a toothed rack supported on the base and extending parallel to the direction of carriage movement with its teeth facing upwardly, a self-contained unit comprising a frame seated in said pocket and removable through the upper open end thereof, bearing means mounted in said frame, a pair of rolls rotatably supported in said bearing means, intermeshing pinions secured to the rolls and a rack-engaging pinion secured to one roll and engaging said rack for imparting rotational movements to the rolls in response to reciprocation of the carriage.
